UNITED STATES PATENT OFFICE.

JAMES A. WARDE, OF CHICAGO, ILLINOIS.

DESIGN FOR A BANK.

57,958.

Specification for Design. Patented May 17, 1921.

Application filed October 25, 1920. Serial No. 419,546. Term of patent 14 years.

To all whom it may concern:

Be it known that I, JAMES A. WARDE, a citizen of the United States, and a resident of the city of Chicago, county of Cook, and State of Illinois, have invented a new, original, and ornamental Design for Banks, of which the following is a specification, reference being had to the accompanying drawings, forming a part thereof.

Fig. 2, is a side view of the same.

I claim:

The ornamental design for a bank, as shown.

Signed at Chicago, in the county of Cook and State of Illinois, this 13th day of October 1920.

JAMES A. WARDE.
